UNITED STATES PATENT OFFICE.

OTTO PRANTE, OF WEST HOBOKEN, NEW JERSEY.

BRAIDING-MACHINE.

No. 920,994.

Specification of Letters Patent. Patented May 11, 1909.

Application filed May 23, 1908. Serial No. 434,526.

To all whom it may concern:

Be it known that I, OTTO PRANTE, a subject of the Emperor of Germany, residing at West Hoboken, in the county of Hudson and 5 State of New Jersey, have invented new and useful Improvements in Braiding-Machines, of which the following is a specification.

By means of this invention patterns or designs can be produced in braids and the invention resides in the following specification and claims and illustrated in the annexed 10 drawing in which:

Figure 1 is a plan view of a machine embodying this invention. Fig. 2 is a section 15 along $\alpha\alpha$ Fig. 1.

In the drawing are shown races or tracks for bobbins which travel along such races or tracks b in top plate 7 as known. The drive wheels c are arranged in pairs each with two 20 prongs or wings or engaging parts for driving the bobbins. Each such gear 6 on the shaft of a driver pair has its members c connected by a driver d to move in unison. The sections of tracks between their respective 25 crossings are of a certain length or extent to accommodate a pair of drive wheels c . At one side the sections of track are crossed by transverse tracks e . A pattern thread guided by or through a tube f is brought between two tracks or clear of the tracks as the 30 pattern thread is set inside or outside the paths of the main bobbins. If the pattern thread is led up inside the main track it is invisible or concealed in the braid but when moved outside the main track the pattern thread is made to appear on the outside of the braid. Designs can thus be produced. As the bobbin is moved by a horn or part of a gear c it comes into reach of a transfer 35 wing or arm i on axle or fulcrum h of a transfer gear k . The transfer arm i as seen operates only in connection with the upper track. By such transfer arm i the bobbin is moved to reach of the next succeeding horn 40 gear c and so on about the various circuits. In each plate or circuit is shown one pair of horn gears and each pair is suitably spaced so as to allow entry into each circuit of a transverse track e without interfering with 45 or striking either horn gear c . Each pair c moves together or form practically one wheel. The transfer gear k is in mesh with one of a pair of horn gears c and a second transfer wheel d by its teeth 6 gears to both 50 of said pair of wheels c . Each wheel c is shown with two horns or bobbin engaging

parts while gear d has three horns. But the invention is not limited to this exact construction.

A jacquard mechanism (not shown) can set 60 the pattern thread at suitable times and into and out of the space between the main tracks. The normal position of the pattern thread f is between the tracks b . Any suitably applied spring can move the pattern thread to 65 normal position. The jacquard at suitable moments withdraws the pattern thread from inside to outside the tracks.

The pattern thread tube f can be moved back and forth along a slide or guide rod m 70 secured at n to a plate o under the plate 7 having the tracks b . The carrier p of the tube f is slid on the rod m by lever q fulcrumed at r and moved by spring s in one direction. The connection or strap f pulled 75 by jacquard (not shown) moves lever q the other way.

The pattern thread is led from a suitable bobbin 2 over guides or wires 3 and kept 80 tight by a slight weight such as a piece of wire 4 hung onto the pattern thread. Stop blocks 5 can be adjusted on rod m to limit the reciprocation of the thread tube f or its slide block p .

What I claim is:—

1. A braiding machine comprising bobbin tracks, a pair of spaced drivers inside the tracks, a transfer wheel geared to one of the drivers and having an arm for moving a bobbin from one of the drivers to the other, 90 another transfer wheel geared to both members of the driver pair, a track made to extend from within the first named tracks to the outside thereof and provided with a movable guide and a pattern thread carried 95 by said movable guide.

2. A braiding machine comprising bobbin tracks, a pair of spaced drivers inside the tracks, a transfer wheel geared to one of the drivers and having an arm for moving a 100 bobbin from one of the drivers to the other, another transfer wheel geared to both members of the driver pair, a track made to extend from within the first named tracks to the outside thereof and provided with a 105 movable guide and a pattern thread carried by said movable guide, each of the spaced drivers having two horns and the second named transfer wheel having three horns.

3. A braid machine having races or paths 110 for the braiding bobbins and a race for a pattern thread bobbin or thread holder, said

pattern thread race being transverse to the other races, the driving wheels for the bobbins being spaced to allow entry into the main track of the transverse track and a driving lever for moving the bobbin over the gap caused by the transverse track.

4. A braid machine comprising driving wheels arranged in pairs, a transfer or connecting device for the drivers at one side of 10 the main track, a transverse track at the

other side of the main track, and a lever to drive a bobbin across the transverse track.

In testimony whereof I have hereunto set my hand in the presence of two subscribing witnesses.

OTTO PRANTE.
